DICE AGITATOR

Max J. Ruderian, 545 Hanley, Los Angeles, Calif.

Filed Dec. 10, 1962, Ser. No. 72,782

Term of patent 14 years

(Cl. D34—5)

Fig. 1

Fig. 2

Fig. 3

FIGURE 1 is a perspective view of a dice agitator showing my new design;

FIGURE 2 is a top plan view thereof, a bottom plan view thereof being substantially identical in appearance; and,

FIGURE 3 is a side elevational view thereof.

The dominant features of my design reside in the portions shown in full lines.

I claim:

The ornamental design for a dice agitator, substantially as shown and described.
